UNITED STATES PATENT OFFICE.

RALEIGH J. HIMMELRIGHT, OF ENGLEWOOD, AND ALFRED H. WILLETT, OF WEST NEW YORK, NEW JERSEY.

FIRE-PAN CONSTRUCTION FOR OIL-BURNING FIRE BOXES.

1,406,732.

Specification of Letters Patent. Patented Feb. 14, 1922.

Application filed May 20, 1920. Serial No. 382,741.

To all whom it may concern:

Be it known that we, RALEIGH J. HIMMELRIGHT and ALFRED H. WILLETT, both citizens of the United States, residing at Engle-

wood, in the county of Bergen and State of New Jersey, and at West New York, in the county of Hudson and State of New Jersey, respectively, have invented certain new and useful Improvements in Fire-Pan Construction for Oil-Burning Fire Boxes, of which the following is a specification.

This invention relates primarily to the provision of a construction of the character specified which is particularly applicable

to locomotive fire boxes, and in connection with the following description we have illustrated it as embodied in such a fire box. Such pans are lined with refractory bricks and are designed to close the bottom of the fire box

and to provide a flame-way channel having communication with the combustion space of the fire box. A suitable burner or burners project through openings either at the forward end of the channel or at the back end.

To our knowledge these oil or fire pans are commonly made up from ordinary tank steel or boiler plate and angle irons. In a great many cases the pans are constructed generally in the simplest manner to suit individual fire boxes, and little, if any, consider-

ation is given to the bricking requirements, the results being unsatisfactory in many cases due to the amount of patch work necessary for the bricking.

It has also been proposed to cast these pans in a single piece, but this of necessity requires the provision of a separate pan for each size or shape of fire box. If this method be followed the number of patterns which it is necessary to carry in stock is almost prohibitive.

The principal object of our invention is to provide a simple means for constructing these pans which will avoid the above difficulties and yet be comprehensive enough to take in the entire scope of the locomotive fire box field.

More specifically it is the object of our invention to provide what we have termed "standard ends" for the fire pans between which is supported the section of tank steel or boiler plate from which the pan is made. These ends are separate castings, one for each end of the pan, which are adapted to be secured in any suitable or desired manner to the mud ring of the fire box. With two or

three sizes of standard ends it is possible to provide for practically all of the various sizes and shapes of fire boxes now in use on locomotives.

A further object of our invention and one which is incidental to the foregoing is the standardization of the bricking with which the pans are lined. With certain fixed standards in the sizes of the pans it is possible to utilize standard bricks in standard arrangements and this with an absolute minimum of what is termed "patching." This is very important, as in service patch work bricking tends to jar loose necessitating frequent re-

pairs.

It is a further object of our invention to provide a construction of the character specified which will permit of placing the pan horizontally in the fire box irrespective of the slope of the mud ring.

These, together with such other objects as may hereinafter appear or are incident to our invention we obtain by means of a construction which we have illustrated in preferred form in the accompanying drawings, wherein

Figure 1 is a central, vertical, longitudinal section through a locomotive fire box embodying our improvements; Figure 2 is a section on the line 2-2 of Figure 1; Figure 3 is a section on the line 3-3 of Figure 1; Figure 4 is a section on the line 4-4 of Figure 1; Figure 5 is a central vertical longitudinal section through the lower portion of a locomotive fire box embodying a modified form of our invention; Figure 6 is a section on the line 6-6 of Figure 5; Figure 7 is a section similar to that of Figure 3 but illustrating our invention as embodied in a "radial" pan as distinguished from the channel shaped pan of the other figures; Figure 8 is a section on the line 8-8 of Figure 2 illustrating the standard ends and the pan in side elevation; Figure 9 is a section on the line 9-9 of Figure 6; and Figure 10 is a detailed view of the pan construction illustrated in Figures 5, 6 and 9.

Referring to the drawings and particularly to Figures 1 to 4 inclusive it will be seen that the fire box, briefly described, comprises the usual crown sheet 1, flue sheet 2, inside side sheets 3, outside side sheets, 4 inside back sheet 5 and outside back sheet 6, through which is provided the usual door opening 7. The forward water leg 8, the rear water leg 9 and the side water legs 10

are closed at the bottom by the customary mud ring 11. The bottom of the fire box chamber A formed by the above parts is closed by means of the pan and brick construction now to be described.

Supported by and extending between the forward channel shaped casting 12 and the similarly shaped rear casting 13 is the channel shaped oil or fire pan 14 through the bottom of which there is the customary clean out and air inlet opening 15. Extending beneath and supporting each casting is a suitably bent T-iron 16 which we propose to secure in any preferred manner to the mud ring 11. These T-irons form the foundation support, so to speak, for the entire pan construction.

At their upper edges the castings, as shown, are provided with horizontally projecting flanges 17 which cooperate with suitable angle irons 18 attached to the walls of the fire box to support the side plates 19 and the end plates 20. The end plates 20 extend transversely of the fire box from one inside sheet to the other and cover the distance longitudinally between the front and back sheets and the forwardly and rearwardly projecting flanges 17 of the standard end castings. The side plates extend longitudinally of the fire box substantially from end to end of the fire pan and cover the distance transversely between the side flanges of the end castings and the inside side sheets of the fire box.

35 In the embodiment shown the forward casting 12 is provided with a suitable burner opening 21 and is constructed to carry the burner 22.

By providing two or three standard sizes 40 of the standard ends or castings it is possible to take care of the entire scope of the locomotive fire box field. Variations in width or depth are taken care of by the castings themselves and variations in 45 length are taken care of by cutting from pans of correspondingly standardized widths, the length suitable or desirable for the particular locomotive to which the application is being made. This is a comparatively simple matter for any railroad 50 shop to handle. The distances between the ends of the pan and the inside front and back sheets and the distances between the pan and the inside side sheets are readily taken care of by varying the sizes of the end plates and of the side plates.

The pans are provided with a refractory lining composed of a plurality of bricks 23, the sizes and arrangement of which it will be 55 readily understood, can be standardized in conformity with the standard ends or castings. In other words for any given size or character of pan, as determined by the shape and size of the ends utilized, there can easily be provided a standard bricking arrange-

ment. This will practically eliminate all necessity for patch work construction.

At the back end of the fire box opposite the burner we provide the refractory flash wall B. The spaces between the forward 70 end of the pan and the forward water leg 8 and between the sides of the pan and the side sheets 3 are covered by means of the refractory floor wall composed of a plurality of bricks and indicated as a whole by 75 the reference character C.

By the construction above disclosed, it will be seen that we have taken care of the most difficult of the bricking problems, namely, the cross sectional bricking of the 80 pan and this in a very simple and efficient manner.

In considering the foregoing description, reference should also be had to Figure 8 as well as to Figures 1 to 4 inclusive. If desired, in the ends of the pans and the castings at the points where they overlap, suitable holes may be drilled through which can be placed bolts which will aid in providing a firm construction. In Figures 3 and 8 I have indicated such an arrangement, referring to the holes by the reference character 85 90 24, and to the bolts by the reference character 25, but in the other figures they have been omitted in order to avoid confusion in the 95 drawing.

The disclosures of Figures 5, 6, 9 and 10 is substantially identical with that already considered with but one or two exceptions. In these figures the pan 12' instead of having its sides of equal depth throughout the length of the pan, has them sloping to follow the line of the mud ring. To retain the advantages of standard bricking, however, we attach to each side of the pan 12' a projecting plate 12'', which plates are fixed thereto by means of suitable bolts or rivets 105 26. In this construction the space between the sides of the pan and the mud ring is closed off by means of a longitudinally extending plate 27 as most clearly shown in Figure 6. Where these plates are used, in order to avoid duplication, the side plates 19 are dispensed with, the outer ends of the 110 bricks constituting the side portions of the floor B being supported upon angle irons 28 affixed to the inner side sheets. In case it were necessary to work upon the stay bolts 29, which are covered in the arrangements of Figures 1 to 4 inclusive and 8, particularly at those points where the pan extends 115 upwardly above the mud ring a considerable distance, as clearly shown in Figure 3, all that it is necessary to do in the arrangement disclosed in Figures 5, 6, 9 and 10, is to remove the side plates 12''.

From the foregoing it will be seen that by providing standard ends the fire pans can be constructed with very great simplicity. The ends act as templets or forms to which 120 125 130

the sides and bottom of the pans may be attached. One size of end castings will answer for a number of sizes of fire box widths, variation being taken care of by providing different widths of side plates between the pans and the side of the fire box. Also, as previously pointed out, the scheme has the additional advantage of providing means whereby a uniform bricking assembly can be adopted.

We claim:

1. An oil burning locomotive fire box construction comprising in combination, a pair of fire pan forming members constituting a gauge or templet for the pan, means for supporting said members from the mud ring, and a separable fire pan adapted to be supported by said members.

2. An oil burning locomotive fire box construction comprising in combination a fire pan casting for each end of the fire box constituting a gauge or templet for the pan and a separable fire pan supported by and extending between said castings.

3. An oil burning pan construction for locomotives adapted to permit the use of a standard arrangement of refractory lining bricks, comprising in combination, a pair of end forming members, means for supporting them from the fire box, and a separable pan extending between and supported by said end forming members.

4. An oil burning pan construction adapted to be applied to locomotive fire boxes of

varying sizes comprising in combination, a pair of standardized end castings, a separable pan extending between said castings and a refractory lining for the pan and the castings composed of a standardized arrangement of bricks.

5. An oil burning locomotive fire box construction comprising in combination; side sheets, forward and back sheets and a mud ring; a pair of fire pan forming members of a width narrower than the distance between the side sheets; means for supporting said members from the mud ring; a separable pan adapted to extend between and to be supported by said members; a refractory lining for the pan and said members; and refractory floor walls extending from the pan to the said sheets.

6. An oil burning pan construction adapted to be applied to locomotive fire boxes of varying sizes comprising in combination, a pair of end castings, means for supporting said castings from the fire box, a pan extending between and supported by the end castings, the pan and castings being together of a size smaller than that of the fire box to which they are applied, and means for closing the spaces between the sides and ends of the pan and castings and the walls of the fire box.

In testimony whereof we have hereunto signed our names.

RALEIGH J. HIMMELRIGHT.
ALFRED H. WILLETT.
